VAPOR LIGHT COMPANY, OF FREEPORT, ILLINOIS, A CORPORATION.

VAPOR-LAMP.

1,231,673.

Specification of Letters Patent.

Patented July 3, 1917.

Application filed October 25, 1915. Serial No. 57,696.

To all whom it may concern:

Be it known that we, IRA ULFERS and FRED C. ASIMOS, citizens of the United States, and residents of Freeport, county of 5 Stephenson, and State of Illinois, have invented certain new and useful Improvements in Vapor-Lamps, of which the following is a specification.

The invention relates to vapor lamps and 10 seeks to provide a simple, efficient construction having means for vaporizing liquid fuel, mixing the vapor with air and burning the mixture to heat a mantle to incandescence, the construction being such that the 15 parts can be readily taken apart for cleaning and removing any deposited carbon. The invention consists in the features of improvement hereinafter set forth, illustrated in the preferred form in the accompanying drawings and more particularly pointed out in the appended claims.

In the drawings: Figure 1 is a vertical section of the improved lamp. Fig. 2 is a detail section on an enlarged scale on the 25 line 2—2 of Fig. 1. Fig. 3 is a view in elevation of the parts shown in Fig. 2. Fig. 4 is a view of a tool which is used to clean the generator pipe of the lamp.

Vapor lamps usually comprise a supply 30 tank adapted to contain liquid fuel under pressure, a vapor generator pipe provided with a mixing chamber and a burner, and suitable valve mechanism for controlling the flow of the liquid fuel from the supply tank 35 to the generator pipe. Such lamps, particularly if kerosene is used, are apt to be clogged by deposits of carbon. The present invention provides a simple construction which will operate efficiently and also in 40 which the parts may be readily disassembled for cleaning and for removing any deposited carbon.

The fuel supply tank or bowl preferably 45 constitutes the lamp base and is formed of an upper bell-shaped shell 1 and a dished bottom 2. The shell 1 is provided with a reverted or U-shaped flange 3 at its edge and the bottom 2 is provided with a down turned flange 4 extending between the members 50 of the U-shaped flange 3 and secured thereto to form a tight joint. The central top portion or neck 5 of the tank is thickened and is provided with a flat upper face and an internally threaded opening. A cylindrical bushing or valve casing 6 is remov-

ably mounted upon the neck 5 of the supply tank. Preferably, a coupling plug 7 is securely threaded into a socket formed in the lower end of the bushing 6 and this plug is removably threaded into the neck 5 of the 60 tank. A packing ring 8, preferably of rubber cork compound, surrounds the coupling plug 7 interposed between the bushing 6 and neck 5 of the tank to form a tight joint between these parts. Preferably, as shown, 65 the packing ring is arranged within a seat formed in the lower face of the bushing 6. A fuel supply pipe 9 is threaded at its upper end into the bore of the coupling plug 7, or is otherwise suitably secured thereto, 70 and this pipe depends into the tank to a point adjacent the bottom thereof. The bushing or valve casing 6 is provided at its lower end with a series of openings 10 adapted to be engaged by a suitable spanner 75 wrench, so that the bushing 6 and fuel supply pipe 9 can be removed from the tank and these parts can then be readily cleaned.

A passageway 11 for liquid fuel extends through the valve casing or bushing 6 and the flow therethrough is controlled by a needle valve 12. The latter is provided with an enlarged portion 13 which is threaded into a transverse bore formed in the bushing 6. The outer end of this bore is enlarged to form a stuffing box 14 around the stem of the valve. A gland 15 is threaded into the stuffing box and compresses the packing 16 therein around the valve stem.

Suitable means is provided for supplying 90 liquid fuel and air under pressure to the tank. For this purpose a nipple 17 extends through an opening in the upper portion of the tank and is provided with an enlarged outer end and a screw-threaded portion that 95 engages a nut or washer 18, that is soldered to the inner wall of the tank. A valve casing 20 is arranged within the nipple and is provided with a flange 21 which overlaps the outer end thereof. A packing ring 19 100 seated in a groove in the flange 21 forms a tight joint between the valve casing and the nipple. A cap 22 extending over the flange 21 is threaded on the outer end of the nipple and holds the valve casing in place. The 105 bore of the valve casing 20 is provided with an inwardly opening ball-check valve 23 and a hollow needle valve 24. By removing the cap 22 and the valve casing 20, liquid fuel can be placed in the tank. By merely loosen- 110

ing the valve 24, air can be forced into the tank to place the liquid fuel therein under pressure and, when the desired pressure is reached, the valve 24 is closed.

- 5 The bushing or valve casing 6 is provided with a reduced, externally threaded portion 25 having an enlarged bore or recess therein and a cap-shaped nut or coupling 26 is removably threaded thereon. A packing ring 10 27, preferably formed of a rubber cork compound, arranged within a seat in the upper portion of the coupling 26, engages the upper end of the part 25 to form a tight joint therewith, and, for removing the coupling, the latter is provided with openings 15 28 to receive a spanner wrench. The upper portion of the coupling 26 is provided with a bore and the lower end of a generator pipe 29 is securely threaded or otherwise fixed 20 within this bore.

The upper end of the generator pipe is provided with an extension or tip 30 which is provided with a contracted discharge orifice 31 for the generated vapor. The extension or tip 30 is threaded upon the upper end 25 of the generator pipe 29 and, throughout the greater portion of its length, is provided with a bore of the same size as the generator pipe. A mixing chamber and burner are 30 mounted upon the upper end of the generator pipe. In the construction shown, the mixing chamber 32 is cylindrical, is closed at its upper end and at its lower end is provided with an inverted burner head 33 which surrounds the extension or tip of the generator pipe. The cylindrical mixing chamber is provided with a hollow cross-piece or transverse portion 34 which is bored out to form air inlet ports, and, preferably, as 35 shown, air inlet pipes 35 are threaded into these ports. The transverse portion 34 is provided with a depending, internally threaded nipple 36 which is removably threaded on the upper end of the tip or generator pipe extension 30. The part 34 is 40 also provided on its upper side with an internally threaded nipple 37 to which is fixed a pipe 38 that conducts the mixed vapor and air to the upper portion of the mixing chamber. From thence it passes down around the pipe 38 and part 34 to the burner head 33. An open-ended sleeve mantle 39 is adapted to be secured at its lower end in a groove formed in the lower portion of the 45 generator pipe extension 30, and, at its upper end, it is secured to the burner head 33.

A valve rod 40 extends through the generator pipe 29 and its extension or tip 30 and is provided at its upper end with a valve 41 and with a pin or needle 42 for controlling the flow through the discharge orifice 31 and for cleaning the same. The lower end of the valve rod is provided with a disk 43 arranged within the enlarged bore at the 55 upper end of the bushing or valve casing 6.

A rack bar 44 having circular rack teeth thereon is eccentrically fixed to the disk 43 and depends within a socket 45 formed in the bushing 6. As shown, this socket communicates with the small bore 11 of the valve 70 casing 6 and forms part of the fuel passage-way through the valve casing. A pinion 46 engages the teeth of the rack bar 44 and is provided with an operating stem 47. The pinion is arranged within a transverse bore 75 formed therefor in the bushing 6, and the outer end of this bore is enlarged to form a stuffing box 48. A gland 49, threaded in the stuffing box, compresses packing 50 there-in around the stem 47. 80

Adjacent its upper end, the body of the generator pipe 29 is upset to form a shoulder portion 51 which is slightly larger in diameter than the main body of the pipe and which is threaded to receive the lower 85 threaded end of a starting cup 52. The latter, as usual, contains a body of asbestos 53. The enlarged portion or shoulder 51 of the generator pipe forms an abutment for a sleeve 54 which snugly fits the generator 90 pipe. The lower end of the sleeve 54 is threaded to receive a nut or cap-piece 55 and a cylindrical handle 56 of vulcanite, or like insulating material, is held in place about the generator pipe by the nut or cap 55 and 95 the coupling member 26. As shown, the cap 55 and coupling member are provided with reduced portions which fit within the cylindrical handle. In assembling the parts, the tubular sleeve 54 is first slipped onto the 100 generator pipe with its upper end abutting against the enlarged portion 51. The lower end of the generator pipe is then securely fixed to the coupling member 26. The handle 56 is then placed in position with its 105 lower end engaging the coupling member, and the cap nut 55 is then threaded onto the sleeve 54 into engagement with the upper end of the handle. The handle is securely fastened against movement on the generator 110 pipe, since the sleeve 54, to which the cap nut 55 is threaded, abuts against the integral enlarged portion 51 of the pipe. 115

As already noted, the bushing or valve casing 6, together with the supply pipe 9, 115 can be removed from the tank so that the interior of the tank and the passages through the pipe and valve casing can be readily cleaned. By disconnecting the coupling member from the upper end of the bushing, 120 the generator pipe and parts mounted thereon can be readily removed; then, by removing the valve rod 40 from the generator pipe, the interior of the latter can be cleared of carbon by means of a suitable tool 59, such 125 as shown in Fig. 4. In the construction shown, a shade 57 is held in place about the mantle by means of a holder 58 that rests upon the upper end of the mixing chamber 32. 130

It is obvious that changes may be made in the details set forth without departure from the essentials of the invention as defined in the claims.

5 We claim as our invention:

1. In a vapor lamp, the combination of a fuel supply tank adapted to contain fuel under pressure, a bushing removably mounted on said tank, a fuel supply pipe secured 10 within said bushing and depending within said tank, a coupling removably threaded in the upper end of said bushing, a vertical generator pipe secured at its lower end to said coupling and having a discharge orifice 15 at its upper end, said bushing having a passage way therethrough communicating with said supply and generator pipes, a valve rod arranged in said pipe and in the upper portion of said bushing and having a valve and a cleaning pin for said orifice, said valve rod being removable from said bushing and said pipe when said parts are disconnected, and a rotatable stem mounted in said bushing and provided with means for shifting said valve 20 rod and a needle valve mounted in said bushing below said stem for controlling the passage through said bushing, substantially as described.
2. In a vapor lamp the combination of a fuel supply tank adapted to contain fuel under pressure, a bushing removably mounted on said tank and having a passage way therethrough, a fuel supply pipe secured to said bushing and depending within said tank, a coupling removably threaded on the upper end of said bushing, packing interposed between said tank and said bushing and between the latter and said coupling, a vertical generator pipe secured at its lower 25 end to said coupling and having a discharge

orifice at its upper end, a cap nut mounted on said generator pipe and an insulating handle surrounding said generator pipe and held in place between said coupling and said cap nut, substantially as described.

45

3. In a vapor lamp, the combination with a generator pipe, a coupling secured thereto, a sleeve on said pipe, the latter having an integral shoulder against which said sleeve abuts, a cap nut threaded on said sleeve, and an insulating handle surrounding said pipe and interposed between said coupling and said cap nut, substantially as described.

50

4. In a vapor lamp, the combination of a supply tank, a bushing having a passageway therethrough secured to said tank, a coupling removably threaded on said bushing, a vertical generator pipe secured at its lower end to said coupling, a sleeve on said generator pipe, the latter having an integral shoulder against which said sleeve abuts, a cap nut threaded on said sleeve, and an insulating handle surrounding said generator pipe and interposed between said coupling and said cap nut, substantially as described.

60

5. In a vapor lamp, the combination with a bushing having a passageway therethrough, a generator pipe connected to said bushing at one end and having a discharge orifice at its outer end, a valve rod in said pipe having a valve and cleaning pin for said orifice, a rack eccentrically mounted on said valve rod and arranged in said bushing, a stem extending into said bushing in line with the axis thereof, and a pinion on said stem engaging said rack bar, substantially as described.
